PNEUMATIC FEEDING DEVICE FOR PRINTING PRESSES, CHECK CANCELERS, AND THE LIKE

John A. Waller, Beverly Hills, Calif., assignor to Charles P. Mee, Los Angeles, Calif.

Application November 12, 1940, Serial No. 365,295

14 Claims. (Cl. 271—29)

This invention pertains broadly to the art of handling materials in sheet form which are to be conducted to a printing device, perforating machine, or the like, and pertains particularly to a drum type feeding device provided with a self-contained suction-producing member adapted to select a terminal sheet from a plurality of sheets arranged in a pile, stack, or the like, and deliver the same to any desired subsequent operation.

The principal object of the invention is to provide a feeding device of the character described, which will operatively engage a terminal sheet and extract it from a pile or stack of aligned sheets and carry it away from such stack into position to be operated upon by a printing device, cancelling device, perforating device, or the like.

A particular object of the device is to provide a rotary feeding member carrying a self-contained suction-producing means adapted to operate on but one sheet at a time so as to abstract such sheet from the remainder of the sheets without disturbance of such remainder.

A further object of the invention is to provide a feeding device which is cylindrical in form and carries an axially movable piston member internally disposed in position to produce momentary decreases in pressure within the interior of such device in response to a rotary movement thereof.

A further object of the invention is to provide a feeding device which will engage an exposed sheet forming a part of a pile or stack of similar sheets, and move such engaged sheet away from its normal position in a longitudinal direction while preserving the remaining sheets of such pile or stack against such longitudinal movement.

A further object of the invention is to provide a check cancelling device having a rotary feeding device of the character described, in which co-operating timing mechanisms are provided for momentarily halting the longitudinal movement of a sheet withdrawn from a pile of sheets and subjecting such withdrawn sheet to a cancelling or perforating operation without interrupting or interfering with the normal functions of the unit as a whole.

A further object of the invention is to provide a cancelling device useful in connection with such a rotary feeding mechanism, in which removable perforating elements are provided whereby a selective perforation or marking of such sheets may be secured.

A further object of the invention is to provide

a printing device having a cylindrical feeding member of the character described.

The feeding device of the present invention may comprise, essentially, a cylindrical member adapted for rotation about an axis extending transversely to the direction of travel desired to be imparted to the sheets on which the device operates, such cylindrical feeding member being provided with an axially reciprocable piston member constrained to rotate with and disposed interiorly thereof, and movable in an axial direction in response to rotary movement of the feeding member in a timed relationship thereto, together with suitable suction ports located in the periphery of the feeding member in position to provide fluid communication from the interior of such feeding device to the exterior thereof in the immediate vicinity of a sheet on which an operation is to be performed, whereby upon rotation of such rotary feeding device in close proximity to an exposed terminal sheet of a stack or pile of similar sheets, the condition of reduced pressure produced within the rotary feeding device will be produced when such suction ports are in closely spaced relation to such sheet which is to be operated upon so that upon the establishment of such condition of reduced pressure, atmospheric pressure will force such sheet into intimate engagement with the cylindrical feeding member which will impart movement to such sheet along the periphery of such feeding member. Suitable means are provided for engaging such sheet promptly after it is brought into contact with the rotary feeding member whereby its further movement is secured by frictional engagement therewith. Suitable means are preferably provided in association with the feeding drum mechanism for reception of the sheet which is abstracted from such pile or stack and the guiding of such sheet into position to be operated upon by an auxiliary portion of the construction, such as a printing device, a check cancelling member, perforating device, check endorsing member, or the like. Means are preferably provided whereby the longitudinal movement of the abstracted sheet is momentarily interrupted without interruption in the rotary movement of the feeding device, so that a subsequent operation requiring that the feed be held in immobile state can be carried out on the sheet in a timed relation to the rotation of the feeding device, and such sheet subsequently given a further longitudinal movement following the completion of such operation.

The above and further objects of the inven-

tion will be brought out more particularly in connection with the following specific description of certain embodiments of the invention, as illustrated in the accompanying drawings, and referring thereto:

Fig. 1 is a plan view of a combined check-cancelling and check-endorsing device according to this invention;

Fig. 2 is a partly broken-away side elevation thereof;

Figs. 3 and 4 are partly broken-away longitudinal sections taken on lines 3—3 and 4—4 respectively in Fig. 1, illustrating two steps in the operation of the device for successive perforation (cancellation) and printed endorsement of a check or similar item;

Fig. 5 is a fragmentary view of the upper edge portion of the feeding cylinder element of the device taken along the same line as Fig. 3, illustrating the operation thereof in picking off the lowermost of a stack of superimposed sheets of paper, such as a stack of checks;

Fig. 5a is a partly broken-away sectional view taken on line 5a—5a in Fig. 5.

Fig. 6 is a partly broken-away side elevation of the device, from the side opposite that of Fig. 2;

Fig. 7 is a broken-away horizontal section taken on line 7—7 in Fig. 6;

Fig. 8 is a partly broken-away end view of the device, taken from the feeding end;

Fig. 9 is a transverse section taken on line 9—9 in Fig. 6;

Fig. 10 illustrates the appearance of a cancelled and endorsed check which has been operated upon by the device shown in Figs. 1—9; and

Figs. 11 and 12 are side and feed end views, respectively, of a modified form of the invention useful as a printing machine.

Referring particularly to Figs. 1—9, the device may comprise right- and left-hand side frame members 1 and 2 supported in spaced relation through the agency of spacer bars 3. A rotary feeding drum is provided as at 4 supported on a shaft 5 carried by bearings 6 disposed on the side members 1 and 2, a suitable hand wheel 7 being provided whereby rotary movement of said drum may be effected. The drum member 4 is provided with a closed end or wall 8 at its right-hand end and is closed at its left-hand end through the agency of a movable piston member 9 provided with a hub 11 supporting said piston member for slidable axial movement on the shaft 5, said piston member being constrained to rotate with the drum member as through a key 11a, and being biased outwardly or to the left-hand side of the device through the agency of a suitable spring member 12. The desired inward axial movement of the piston 9 is conveniently secured through the agency of a semi-circular cam 13 mounted on the outer end of the piston 9 and positioned to engage a roller 14 pivotally secured on bearing means 15 to the left-hand side frame member 2. Suitable openings are provided in the periphery of the drum 4 as at 16, which are hereinafter referred to as suction ports. The location of these suction ports in relation to the position of the cam 13 is, in this embodiment, preferably such that such ports will be disposed substantially vertically above the axis of rotation defined by the shaft 5 when the high end of cam 13 reaches the position of the roller 14, so that when the outward axial movement of the piston 9 is initiated by the cam 13 falling off the roller 14, the ports 16 will be located in position

to operate upon the lowermost or terminal check of a stack 17 of checks 18, as shown particularly in Fig. 5.

Referring more particularly to Figs. 3, 4 and 5, it will be seen that as the suction ports 16 reach the position indicated in Fig. 5, and release of the piston 9 is obtained by virtue of the cam 13 abruptly dropping off the roller 14, as above described, the spring 12 will force the piston outwardly and cause a condition of reduced pressure to exist within the drum 4. The degree of pressure reduction obtained within the drum 4 will be dependent upon the ratio of the volumes of the cylinder defined by the drum 4 and piston 9 at the inner and outer positions of such piston, as will be apparent to one skilled in the art. This condition causes an inrush of atmospheric air through the ports 16, and this inrush will serve to force the adjacent terminal check or sheet 18a from the stack 17 downwardly into firm engagement with the drum 4, after the manner indicated in dot-dash lines in Fig. 5. An abutment member 21 is provided to position the forward ends or edges of the checks in the stack 17, said abutment member being preferably tapered downwardly and forwardly so that the central portion thereof with respect to the width of the device is brought into close spacing with the periphery of the drum 4, as at 22. As shown in Fig. 5a, the central portion of the abutment member is preferably caused to project downwardly as at 22', and the adjacent peripheral portion of the drum 4 is relieved slightly as by a groove 38', which encourages the delivered check or sheet 18a (Fig. 5) to momentarily bow upwardly at its edge portions as the forward edge passes under the member 21, which serves to disengage said check from a superjacent check or sheet so that but a single check or sheet would be drawn through by the drum 4. After the check 18a is drawn past the member 21, and as the further rotation of the drum member 4 is effected in a clockwise direction as shown in these specific figures the check 18a is carried forwardly (Fig. 3) into engagement between the periphery of the drum 4 and a compression member such as a rubber-tired roller 23 mounted for rotation on a suitable shaft 24 extending transversely of the device. Two such rollers are preferably provided, as shown particularly in Figs. 1, 3, and 9, and these rollers are adapted to cause the check 18a to continue its movement in response to rotation of the drum member 4, by frictional engagement therewith, irrespective of the loss of suction at the ports 16 after the piston 9 reaches the end of its stroke.

In this form of the invention a cancelling or perforating device is provided in position to receive the check picked up by the drum 4 and carried into position for engagement between said drum and the rollers 23. This perforating device is shown generally at 26. The perforating device may comprise two transversely spaced drive rods 27 which are vertically reciprocable in response to operating means hereinafter described, said drive rods carrying at their upper ends a pressure plate 28 adapted to receive a plurality of removable reference characters 29 and 29' provided with downwardly directed perforating pins 29a adapted to establish the desired perforated character on the check or other sheet which is fed to the device (see Fig. 10). The perforating device further comprises a striking plate 31 provided with perforations 32 corresponding in position to the perforating pins 29a,

said striking plate being supported on a frame member 33 suitably secured to the side frame members 1 and 2 above described. The striking plate 31 may be carried forward as at 34, and may be provided with an upper enclosing surface member 35 cooperating therewith to define an entrance chute 36 for reception of the check to be operated upon, and stripper fingers 37 may be provided at the forward portion of the projection 34 at a position closely adjacent the periphery of the drum 4 to further the proper guiding of the check 18a into position to be operated upon by the perforating device. The stripper points or fingers 37 are preferably extended within recessed grooves 38 (as well as within the groove 38' hereinbefore mentioned) provided in the periphery of the drum 4 as indicated in dotted lines in Fig. 3 and in full elevation in Figs. 1 and 8.

The operation of the perforating means 26 is so timed with respect to the rotation of the drum member 4 that the check 18a is carried into some such position as indicated in full lines in Fig. 4, the perforating means being shown in Fig. 4 as being in operation, just ready to strike the check 18a. It is essential that the forward driving action of the drum member 4 be interrupted when the check 18a is to be operated upon by the perforating means, in this specific form of device, and in order to secure this interruption of operation without stopping the rotation of the drum 4 I may relieve the peripheral surface of the drum as at 41, at the position of normal engagement of the rollers 33 with such drum. This relieved section 41 is shown particularly in Fig. 4, and as a result thereof the drum member 4 no longer has a driving engagement with the check 18a and such check will remain in position during the operation of the perforating member 26. The relieved portion 41 of the drum member 4 is of such angular length as to again cause engagement of the check 18a between the drum periphery and the rollers 23 when the operation of the perforating means has been completed and the perforating pins 29a thereon withdrawn from the check. When the rearward end 41a of the recessed portion 41 is brought into alignment with the position of the rollers 23, therefore, the check is engaged and moved forwardly again, and in this embodiment of the invention is carried into position to be operated upon by a printing device or "endorser" which is arranged to receive and operate upon the check after the cancelling operation.

The printing or endorsing device is indicated generally by the reference character 42, and may comprise a back-up drum 43 mounted for rotation on a shaft 44 suitably secured to the side frame members 1 and 2 of the device, said back-up drum being provided with a flat printing surface 45 against which the printing operation may be performed. The printing member may comprise a printing roll 46 rotatably mounted on shaft 47 and carrying a rubber printing type member 48 adapted to be brought into engagement with the surface 45 upon relative rotation of the drum 43 and member 46, the gear ratio which is established between the drum 43 and the member 46 being such as to give equivalent peripheral speed to the two elements. Roller members 49 corresponding to the compression rollers 23 above described are provided in position to engage the periphery 50 of the drum 43 in a manner comparable to the engagement of the rollers 23 with the periphery of the drum 4. The periphery 50 of the drum 43 is provided with relieved sec-

tions 52, corresponding in function and position to the relieved sections 41 of the drum 4, which is of sufficient angular length so that the end thereof indicated at 52a will be brought into engagement with the correspondingly positioned roller 49 when the operation of the perforating device is completed. An inking roller 53 is provided in position to be engaged by the type 48 upon rotation of the member 46, said roller being pivotally mounted on a transversely extending shaft 54.

The driving coordination between the drums 4, 43, printing member 46, etc., is secured through the agency of a gear train indicated more particularly in Fig. 2. This gear train may comprise a drive gear 56 secured to and rotatable with the drum 4, engaging a pinion or idler 57 mounted on a suitable stub shaft 57', and engaging a gear 58 secured to and rotatable with the drum 43. The printing member 46 is driven through the agency of a gear 59 meshing with the gear 58.

Referring particularly to Figs. 6 and 7, the driving structure for causing operation of the perforating member 26 is illustrated as comprising a depressing cam arm 61 adapted to be engaged by a roller 62 which is pivotally mounted on a stub shaft 63 secured to the end wall of the drum member 43, and adapted when so engaged to force the driving rods 27 of the perforating means downwardly. In order to return the perforating means upwardly to the starting position, I provide a return cam arm 64 adapted to be engaged by the roller 62 when said roller has passed out of engagement with the cam arm 61, and to move said arm 64 upwardly to lift the driving rods 27. The showing of this structure in Figs. 6 and 7 represents the position of the driving rods with the perforating means 26 in the operating position shown particularly in Fig. 4, with the roller 62 positioned just ready to pass out of engagement with the arm 61 and to engage the arm 64. Upon further rotation of the drum member 43, the arm 64 will be moved to the position shown in dot-dash lines at 64a, at which time the roller 62 will be in the position indicated in dot-dash lines at 62a. This causes the driving rods to be moved upwardly to the starting position, which carries the cam arm 61 into the dot-dash position indicated at 61a in position to be engaged by the roller 62 when it again approaches the position indicated in full lines.

It will be appreciated that it may be desirable to cause the cancelling device to remain inoperative, so that the construction may be used purely for endorsement through operation of the printing member 46. In order to disengage the perforating means 26 from operative association with the remainder of the construction, I may provide a guide dog 65 slidably mounted on the shaft 44 on which the drum member 43 is disposed, said dog 65 being adapted for axial movement on the shaft 44 and being provided with a medial groove adapted to engage an annular shoulder 67 on the operating roller 62, whereby said roller 62 may be moved axially along the stub shaft 63 into or out of operative engagement position with the cam arms 61 and 64. A suitable operating handle member for the dog 65 is provided such as an operating pin or shaft 68 provided with a thumb knob 69, the pin 68 being carried outwardly through the side wall 2 of the device into a position at which access can be had by the operator.

In like manner it may be desirable to interrupt the operation of the endorsement portion of the construction, whereby the device may be used

simply for the cancellation of checks or the like by operation of the perforation member 26, and for this purpose I may mount the printing roll member 46 on a hub 71 which is rotatably disposed on the shaft 47, said hub member 71 being provided at its right-hand end with a dog 72 adapted to mate with a dog 73 formed in the hub portion 59a of the gear 59. At the other end of the hub 71 I may provide a dog 74 adapted to mate with a fixed dog 75 secured to the frame member 2, the dogs 74 and 75 being adapted to mate upon axial movement of the hub member 71 so that when the dogs 72, 73 are disengaged the dogs 74, 75 become engaged and further rotation of the printing roll member 46 is stopped. Any suitable operating means may be provided for obtaining the desired axial movement of the printing roll 46, such as an annular recess 76 in the hub member 71 adjacent one end thereof, adapted to be engaged by a finger or yoke 77 carried by a shaft or pin 78 slidably mounted in the frame member 2 and projecting outwardly therefrom and terminating in an operating knob 79.

The device of the present invention has been found to operate at a very high speed without causing more than one check or sheet to be withdrawn from the bottom of the pile 17 and passed through the perforation or endorsing section of the construction. The rapid movement of the piston 9 when the cam 13 falls off the roller 4 serves to produce a rapid change in pressure within the interior of the drum 4, causing the prompt application of atmospheric pressure adjacent the suction ports 16, drawing the adjacent check 18a into engagement with the periphery of the operating drum 4. The inward movement of the leading edge of the check 18a, represented in Fig. 5, is practically instantaneous, and is effected before any significant longitudinal travel is imparted to the check. This insures that the leading edge of the check is so closely adjacent the position at which it will pass under the lower portion 22' of the abutment member 21 before its forward movement is more than initiated, wherefore the drag upon the next succeeding check in the stack 17 will not be imposed while there is a strong inward draft about the ports 16, and for this reason there is little tendency to dislodge the next succeeding check from its position in abutment with the member 21. It has been found that the device operates quite satisfactorily even though the checks which are fed to the device are wrinkled and even torn to some extent, and the utilization of an axially reciprocable suction-producing piston member as above described, serves to permit the device to be kept in static and dynamic balance at substantially any desired speed of rotation. This construction is therefore in marked distinction to prior suggested devices which have incorporated radially reciprocable pump members within a feeding drum.

It will be appreciated that any desired type of table and guide means may be provided to receive the stack 17 of checks or the like, such as indicated at 82 and 83. Furthermore, it will be appreciated that while the construction has been illustrated as disposed in an upright position, with the stack of checks 17 arranged for gravity feeding against the periphery of the drum member 4, the device may be disposed on its side or even in an inverted relation, suitable spring biasing means being provided, as will be apparent to one skilled in mechanical arts, to keep the stack 78

of checks or other sheets biased lightly toward engagement with the periphery of the feeding drum 4.

In Fig. 10 I have illustrated the appearance of 5 a cancelled and endorsed check as perforated and printed according to the present device. The check is designated by the reference numeral 18, the perforations being indicated at 85 showing the words and characters "Paid" and "12 4 35," 10 and the imprinting produced by the type member 48 being indicated at 86. The perforation characters indicated at 29 in Figs. 6, 3, and 4, providing the word "Paid" in the example illustrated in Fig. 10 may be formed as a single unit which 15 may be withdrawn from the plate 28 and another unit spelling out the word "Cancelled" or the like may be substituted therefor, it being appreciated that the openings in the plate 28 will be provided in rectilinear fashion to accommodate the insertion of any desired combination of pins 29a. The characters 29' indicated in Figs. 3, 20 4, and 9 may be independent characters each representing a single numeral, and may be securely positioned against the plate 28 through 25 the agency of a clamping bar 87 held in position through the agency of thumb screws 88. It will further be appreciated that a suitable cover member may be provided over the perforating and printing section of the device as at 89, and that 30 side covers 91 may equivalently be provided, fitting into the side frame members 1 and 2, in order to enclose the device.

In Figs. 11 and 12 I have illustrated the application 35 of my feeding device to a printing press, such as might be used by restaurants and the like in the printing of menus or in any instance where an inexpensive device would be particularly desirable, and referring thereto I have shown right- and left-hand frame members at 40 101 and 102, maintained in spaced relation through the agency of spacer bars 103, and carrying a feeding drum 104 mounted for rotation on the frame members through a shaft 105 journaled as at 106 in the side frame members. An operating handle 107 is provided for rotation of 45 the drum, and the drum carries a piston member 109 interiorly thereof, said piston member 109 being provided with a hub 111 slidably disposed on the shaft 105, and a biasing spring 112 being 50 provided to bias said piston member outwardly. As in the prior device, an operating cam 113 is provided, in engagement with a roller member 114 suitably mounted on the side frame member 102, said cam being adapted to cooperate with the roller 114 to secure axial reciprocation of 55 the piston member upon rotation of the drum 104 through the agency of the handle 107.

The drum 104 is provided with suction ports 116 as in the prior device, together with an abutment member 121 having its lower end 122 closely spaced from the periphery of the drum 104. One or more compression rollers may be provided as at 123. The drum 104 will function in a manner comparable to that above described in connection with the first form of the invention and will pick up the lowermost sheet of a pile of sheets such as indicated at 117, said pile of sheets being placed upon a table member 120 and said table member being disposed substantially horizontally and at a level such as to bring the lowermost sheet in peripheral contact with the drum 104. A drive gear 156 is provided on the shaft 105 which is adapted for rotation with the drum 104, and this gear serves to drive the printing portion of the device through the agency of an

idler gear 157 mounted on the stub shaft 151' and a gear 158 which is secured to a back-up roll 159. The printing roll is disposed above the back-up roll as at 160, said printing roll being adapted to carry movable type members such as indicated at 161 and being driven from the gear 158 through a gear 162. A suitable inking roller for the type drum 160 is provided as at 163. A suitable cover may be provided over the inking roll and the roll 160, as at 164.

It will be appreciated that the spacing between the periphery of the cylindrical feeding member and the adjacent edge of the abutment member, as between the edges 22 and periphery of the drum as well as between the projection 22' and the bottom of the groove 32', will be such as to allow a sheet to pass under the abutment member. Usually, this spacing will be just slightly greater than the thickness of the thickest sheet which the device is called upon to feed, and the device will operate on sheets of varied thickness up to that maximum. For example, when the abutment member is adjusted to pass 24 lb. bond paper, the machine will still feed sheets of 9 lb. "onion skin" paper without difficulty.

Various modifications of the invention will occur to those skilled in the art, and I do not choose to be limited to the precise details herein delineated and described but rather to the scope of the subjoined claims.

I claim:

1. In combination with guide means adapted to receive in stacked relation a plurality of sheets on which a feeding operation is to be performed, said guide means being adapted to receive such stacked plurality of sheets in such relation that a terminal sheet of such stacked plurality is exposed over a portion of its area, a pneumatic feeding device which comprises: frame means; a cylindrical drum member mounted for rotation on said frame means in close peripheral proximity to such terminal sheet at such exposed area; an axially reciprocable piston member constrained to rotate with and slidably mounted within said drum member and defining therewith a suction chamber; means defining a fluid passage communicating with said suction chamber and opening through the periphery of said drum member at one circumferential position; and means for effecting axial reciprocation of said piston member to produce a suction stroke upon rotation of said drum member through a portion of a revolution thereof in one direction, said means including cooperating cam means on said piston member and said frame means, the angular relation of said cam means with respect to each other and to said one circumferential position being such as to cause the peripheral opening of said fluid passage to be located at least closely adjacent said exposed portion of said terminal sheet when said suction stroke is initiated.

2. The construction set forth in claim 1, and comprising in addition an abutment member secured to said frame means and positioned to engage the ends of the sheets of such stacked plurality at one end thereof, said abutment member being spaced from said point of contact forwardly in the direction of rotation of said drum member and having a portion closely spaced from the periphery of such drum member.

3. In combination with guide means adapted to receive in stacked relation a plurality of sheets on which a feeding operation is to be performed,

said guide means being adapted to receive such stacked plurality of sheets in such relation that a terminal sheet of such stacked plurality is exposed over a portion of its area, a pneumatic feeding device which comprises: frame means; a cylindrical drum member mounted for rotation on said frame means, said drum member being provided with a peripheral portion positioned in contact with such terminal sheet at such exposed area; an axially reciprocable piston member slidably mounted within said drum member and defining therewith a suction chamber; means for effecting axial reciprocation of said piston member to produce a suction stroke upon rotation of said drum member in one direction, said means including cooperating cam means on said piston member and said frame means; means defining a fluid passage communicating with said suction chamber and extending through said peripheral portion of said drum member, the position of said fluid passage being angularly so related to said cooperating cam means as to be located at least closely adjacent the point of contact between said drum member and the exposed area of said terminal sheet when said suction stroke is initiated, whereby upon rotation of said drum member suction will be applied to said terminal sheet at such exposed area and a forward motion in the direction of rotation of said drum member will be imparted to said terminal sheet; and a compression member positioned forwardly of such point of contact in the direction of movement imparted to said terminal sheet and having a portion positioned to frictionally engage the periphery of said drum member and adapted to engage said terminal sheet in its forward movement to force said sheet into frictional engagement with said drum member.

4. The construction set forth in claim 3 and comprising in addition an abutment member located between said point of contact and said compression member in the direction of travel of said terminal sheet, said abutment member being adapted to engage said stacked plurality of sheets at the forward ends thereof and having a portion closely spaced from the periphery of said drum member.

5. In combination with guide means adapted to receive in stacked relation a plurality of sheets on which a feeding operation is to be performed, said guide means being adapted to receive such stacked plurality of sheets in such relation that a terminal sheet of such stacked plurality is exposed over a portion of its area, a pneumatic feeding device which comprises: frame means; a cylindrical drum member mounted for rotation on said frame means, said drum member being provided with a peripheral portion positioned in contact with such terminal sheet at such exposed area; an axially reciprocable piston member slidably mounted within said drum member and defining therewith a suction chamber; cooperating cam means on said piston member and said frame means to effect inward axial movement of said piston member upon rotation of said drum member in one direction to effect a decrease in the volume of said suction chamber; biasing means resiliently opposing such inward movement of said piston member and adapted to effect outward movement of said piston member upon completion of such inward movement to produce a suction stroke upon further rotation of said drum member in said one direction; and means defining a fluid passage

communicating with said suction chamber and extending through said peripheral portion of said drum member, the position of said fluid passage being angularly so related to said cooperating cam means as to be located at least closely adjacent the point of contact between said drum member and the exposed area of said terminal sheet when said suction stroke is initiated.

6. The construction set forth in claim 5, and comprising in addition an abutment member secured to said frame means and positioned to engage the sheets of such stacked plurality at one end thereof, said abutment member being spaced from said point of contact forwardly in the direction of rotation of said drum member and having a portion closely spaced from the periphery of such drum member.

7. A pneumatic feeding device which comprises: frame means; a cylindrical drum member mounted on said frame means for rotation about a horizontally extending axis; an axially reciprocable piston member constrained to rotate with and slidably mounted within said drum member and defining therewith a suction chamber; means defining a fluid passage opening through the periphery of said drum member and establishing fluid communication with said suction chamber; means for effecting axial reciprocation of said piston member to produce a suction stroke upon rotation of said drum member through a portion of a revolution thereof in one direction, said means including cooperating cam means on said piston member and said frame means and spring means biasing said piston member outwardly to maintain said cooperating cam means in operative engagement, the position of said fluid passage being angularly so related to said cooperating cam means as to be located at least closely adjacent a position generally vertically above said axis when said suction stroke is initiated; and guide means adapted to receive in stacked relation a plurality of sheets on which a feeding operation is to be performed, with such plurality of sheets being alined longitudinally in the direction of movement of the upper periphery of said drum member and with the lower surface of the lowermost sheet in said stack in close proximity to the periphery of said drum member at said position generally vertically above said axis.

8. The construction set forth in claim 7 and comprising in addition an abutment member secured to said frame means in position to engage the forward ends of said stacked sheets, said abutment member being located in a forwardly spaced relation to the point of contact of said drum member with said lowermost sheet.

9. A pneumatic feeding device which comprises: frame means; a cylindrical drum member mounted on said frame means for rotation; an axially reciprocable piston member constrained to rotate with and slidably mounted within said drum member and defining therewith a suction chamber; means defining a fluid passage opening through the periphery of said drum member and establishing fluid communication to said suction chamber; means for effecting axial reciprocation of said piston member to produce a friction stroke upon rotation of said drum member through a portion of a revolution thereof in one direction, said means including cooperating cam means on said piston member and said frame means and spring means biasing said piston member outwardly to maintain said cooperating cam means in oper-

ative engagement; guide means adapted to receive in stacked relation a plurality of sheets on which a feeding operation is to be performed, with such plurality of sheets being alined longitudinally in the direction of rotation of said drum member in such relation that a terminal sheet of such stacked plurality is exposed over a portion of its area and located in close proximity to the periphery of said drum member at such exposed area, the angular relation of said cam means with respect to each other and with respect to the peripheral opening of said fluid passage being such as to cause such peripheral opening to be located at least closely adjacent said exposed portion of said terminal sheet when such suction stroke is initiated.

10. A pneumatic feeding device which comprises: frame means; a cylindrical drum member mounted on said frame means for rotation about its axis; an axially reciprocable piston member constrained to rotate with and slidably mounted within said drum member and defining therewith a suction chamber; means defining a fluid passage communicating with said suction chamber and opening through the periphery of said drum member at one circumferential position; means for effecting axial reciprocation of said piston member to produce a suction stroke upon rotation of said drum member through a portion of a revolution thereof in one direction, said means including cooperating cam means on said piston member and said frame means; guide means adapted to receive a plurality of sheets in stacked alinement and support the same in such relation to said drum member that a terminal sheet of such stacked plurality is caused to extend in a generally tangential relation to the periphery of such drum member and in close proximity thereto at the position of substantial tangency; and abutment means mounted in fixed relation to said frame means and positioned to engage the ends of such sheets in such stacked alinement at a position forwardly spaced from such position of substantial tangency in the direction of movement of said drum member at said position of substantial tangency, said abutment member having a portion closely spaced from the periphery of said drum member, and the angular relation of said cam means with respect to each other and with respect to said peripheral opening being such as to cause said peripheral opening to be located at least closely adjacent said position of substantial tangency when said suction stroke is initiated.

11. In a sheet feeding device, a suction feeding member which comprises: a cylindrical drum member mounted for rotation about its axis, and an axially reciprocable piston member constrained to rotate with and slidably mounted within said drum member and defining therewith a suction chamber, said drum member being provided with a suction port in the side wall thereof providing fluid communication between said suction chamber and the exterior of said drum member at the periphery thereof.

12. A pneumatic feeding device which comprises: frame means; guide means mounted on said frame means and adapted to receive, in stacked relation, a plurality of sheets on which a feeding operation is to be performed, said guide means including an abutment member positioned to engage the sheets of said stacked plurality at one end thereof, and being further adapted to receive said stacked plurality of sheets in such

relation that a terminal sheet thereof is exposed over a portion of its area at said one end; a cylindrical feeding member mounted for rotation on said frame means and having its periphery disposed in close proximity to said terminal sheet at said exposed area thereof at one position with respect thereto, a portion of the periphery of said feeding member defining a suction portion movable through said one position upon rotation of said member; means for rotating said member; and means for producing a suction at said suction portion as the same is passed through said one position, whereby said terminal sheet is caused to move toward and into engagement with the periphery of said cylindrical feeding member for forward movement therewith upon rotation thereof, said cylindrical feeding member being provided with a circumferentially extending recess in its periphery, and said abutment member extending transverse to the direction of movement of the periphery of said cylindrical feeding member at said one position, and having a portion closely spaced from such periphery at the position of said recess, and being spaced forwardly of said one position in said direction of movement.

13. A pneumatic feeding device for feeding sheets to a perforating member, which comprises: frame means; guide means mounted on said frame means and adapted to receive, in stacked relation, a plurality of sheets on which a feeding operation is to be performed, said guide means including an abutment member positioned to engage the sheets of said stacked plurality at one end thereof, and being further adapted to receive said stacked plurality of sheets in such relation that a terminal sheet thereof is exposed over a portion of its area at said one end; a cylindrical feeding member mounted for rotation on said frame means and having its periphery disposed in close proximity to said terminal sheet at said exposed area thereof at one position with respect thereto, a portion of the periphery of said feeding member defining a suction portion movable through said one position upon rotation of said member; means for rotating said member; means for producing a suction at said suction portion as the same is passed through said one position, whereby said terminal sheet is caused to move toward and into engagement with the

periphery of said cylindrical feeding member for forward movement therewith upon rotation thereof; and compression means disposed forwardly of said abutment member in position to cause frictional engagement of said terminal sheet against the periphery of said cylindrical feeding member upon movement of said sheet past said abutment member, to effect further forward movement of said sheet upon further rotation of said feeding member into position to be operated upon by such perforating member, the periphery of said cylindrical feeding member being relieved at the position of said compression means to cause a release of said frictional engagement of said sheet upon movement of said sheet into received position with respect to said perforating member, the circumferential length of the relieved portion of the periphery of said cylindrical feeding member being such as to cause such release to remain effective during the operation of said perforating member and to re-establish said frictional engagement of said sheet following termination of the operation of said perforating member.

14. A sheet-feeder construction which comprises: frame means; guide means mounted on said frame means, said guide means being adapted to receive, in stacked relation, a plurality of sheets on which a perforating operation is to be conducted, and including an abutment member positioned to engage said sheets at one end thereof, said guide being further adapted to receive said stacked plurality in such manner as to expose a portion of the area of a terminal sheet thereof at said one end; a rotary feeding member adapted to frictionally engage such terminal sheet and carry the same forwardly to a position past said abutment member into received position within a perforating device disposed forwardly of said abutment member; means for interrupting the frictional engagement of said sheet by said rotary feeding member during a given portion of one revolution thereof to cause cessation of forward movement of said sheet; and operating means associated with said rotary feeding member which will cause operation of such perforating device during said portion of one revolution.

JOHN A. WALLER.
